GLASS HOLDER

William Roy Kirsch, 701 J St., Lincoln, Nebr. 68508

Filed Sept. 23, 1966, Ser. No. 3,999

Term of patent 14 years

(Cl. D44—10)

FIG. 1 is a front elevational view of a glass holder showing my new design;

FIG. 2 is a right side elevational view; and

FIG. 3 is a top plan view.

I claim:

The ornamental design for a glass holder, as shown and described.
